INVENTOR:
John L. Rupp,
BY A. Z. Vencall
the ATTORNEY

UNITED STATES PATENT OFFICE.

JOHN L. RUPP, OF WILKINSBURG, PENNSYLVANIA, ASSIGNOR TO WESTINGHOUSE UNION BATTERY COMPANY, OF SWISSVALE, PENNSYLVANIA, A CORPORATION OF PENNSYLVANIA.

STORAGE-BATTERY JAR.

Application filed August 24, 1922. Serial No. 584,128.

To all whom it may concern:

Be it known that I, JOHN L. RUPP, a citizen of the United States, residing at Wilkinsburg, in the county of Allegheny and 5 State of Pennsylvania, have invented certain new and useful Improvements in Storage-Battery Jars, of which the following is a specification.

My invention relates to jars. Jars constructed in accordance with my invention are particularly suited for use as storage battery containers, although the invention is not limited to this particular adaptation.

One feature of my invention is the provision of a jar having integral therewith lugs or shelves which support the plate rests.

I will describe one form of jar embodying my invention, and will then point out the 20 novel features thereof, in claims.

In the accompanying drawings, Fig. 1 is a plan view of a jar embodying my invention, Fig. 2 is a partial vertical section on the plane II-II in Fig. 1, and Fig. 3 is a 25 partial vertical section on the plane III-III in Fig. 1. Fig. 4 is a detail view showing a modification of a portion of the jar shown in Figs. 1, 2 and 3.

Similar reference characters refer to similar parts in each of the views.

Referring to the drawings, the jar, which may be of glass, hard rubber, or any material impervious to the action of the electrolyte and is electrically non-conducting, comprises, as usual, four side walls 1, 2, 3 and 4; and a bottom 15.

Located on the inner side of wall 2 are two lugs 5 and 6, and also located on the inner side of wall 4 are two similar lugs 7 and 8, the lugs 5 and 7 being oppositely disposed and the lugs 6 and 8 being also oppositely disposed. These lugs are integral with the wall of the jar. Each lug comprises a shelf *c* and two guides *a* and *b*. The lugs 5 and 7 serve to support a plate rest 9 which is seated on the shelf *c* of these lugs and is held in proper vertical position by the guides *a* and *b*. The other two lugs 6 and 8 serve to support a plate rest 10 in similar manner. The plate rests 9 and 10 are spaced from the bottom of the jar and may be of the same material as the jar, or any material with similar characteristics, and are provided with openings 11 to permit 55 free circulation of the electrolyte.

One important feature of my invention is that the shelf surfaces *c*, being formed by the plunger of the mold, and having a very small surface present to warp, will be on a plane practically parallel with the top of 60 the jar. The advantage of this is that the support for the plates is parallel to the top of the jar irrespective of irregularities in the bottom of the jar.

In order to insure a snug fit between the 65 rests 9 and 10 and the shelves and guides of the lugs 5, 6, 7 and 8, I prefer to provide a band of rubber 12 around each end of each rest as shown in Fig. 4, this band acting as a cushion between the rests and the supporting lugs.

Although I have herein shown and described only one form of battery jar embodying my invention it is understood that various changes and modifications may be made 75 therein within the scope of the appended claims, without departing from the spirit and scope of my invention.

Having thus described my invention, what I claim is:

1. A storage battery jar having lugs integral with the sides of the jar, plate rests supported by said lugs, and rubber bands on said rests for cushioning the rests on said lugs.

2. A storage battery jar having lugs integral therewith, each lug comprising a shelf and a pair of guides, and plate rests seated on said shelves and held in proper position by said guides, said rests being provided with openings to facilitate circulation of the electrolyte.

3. A storage battery jar having lugs integral therewith, each lug comprising a shelf and a pair of guides, and plate rests seated 95 on said shelves and held in proper position by said guides and spaced from the bottom of said jar, and rubber bands placed around the ends of said plate rests to cushion them from the lugs.

4. A storage battery jar provided with separate plate rests supported on lugs integral with the jar, said rests being spaced from the bottom of the jar and provided with transverse openings to facilitate circulation of electrolyte.

In testimony whereof I affix my signature.

JOHN L. RUPP.

Certificate of Correction.

It is hereby certified that in Letters Patent No. 1,505,166, granted August 19, 1924, upon the application of John L. Rupp, of Wilkinsburg, Pennsylvania, for an improvement in "Storage-Battery Jars," an error appears in the printed specification requiring correction as follows: Page 1, strike out lines 81 to 85, comprising present claim 1, and insert instead—

1. A storage battery jar having two shelves of comparatively small area projecting inwardly from the sides of the jar, and a plate rest supported by said shelves and spaced from the bottom of the jar.;
and that the said Letters Patent should be read with this correction therein that the same may conform to the record of the case in the Patent Office.

Signed and sealed this 28th day of October, A. D. 1924.

[SEAL.]

KARL FENNING,
Acting Commissioner of Patents.
